UNITED STATES PATENT OFFICE.

ALEXANDER KAGAN, OF NEW YORK, N. Y., ASSIGNOR, BY MESNE ASSIGNMENTS, TO WEINER BROTHERS, INC., OF NEW YORK, N. Y., A CORPORATION OF NEW YORK.

DESIGN FOR PRINTED CLOTH.

Application filed February 6, 1925. Serial No. 12,285. Term of patent 3½ years.

To all whom it may concern:

Be it known that I, ALEXANDER KAGAN, a citizen of the Republic of France, residing at New York, in the county of Bronx and State of New York, have invented a new, original, and ornamental Design for Printed Cloth, of which the following is a specification, reference being had to the accompanying drawing, forming part thereof.

The drawing represents a piece of printed cloth, showing my new design.

I claim:

The ornamental design for printed cloth, as shown.

AL. KAGAN.
